UNITED STATES PATENT OFFICE.

JOHN McDONALD HATTERSLEY, OF BIRMINGHAM, ENGLAND.

MEMORANDUM OR WRITING APPLIANCE FOR USE IN CONNECTION WITH TELEPHONES.

1,390,705.

Specification of Letters Patent. Patented Sept. 13, 1921.

Application filed February 7, 1920. Serial No. 357,085.

To all whom it may concern:

Be it known that I, JOHN McDONALD HATTERSLEY, a subject of the King of Great Britain, residing at Association Buildings, 5 Dale End, Birmingham, in the county of Warwick, England, have invented certain new and useful Improved Memoranda or Writing Appliances for Use in Connection with Telephones; and I do hereby declare the following to be a full, clear, and exact description of the same.

The present invention comprises a new or improved memoranda or writing appliance for use in connection with telephones and it 15 has for its object to provide an improved and more effective appliance for this purpose.

According to this invention the appliance is adapted to be secured to the base of a 20 table telephone in such a manner that it is movable therewith, and it comprises a writing base or surface and a paper supply device.

According to one construction the base 25 portion of the appliance is made from two disks of metal separated one from the other in such manner as to form a channel to allow a strip of paper to pass between them, or to allow a sliding writing base to be inserted therein. The writing base may be 30 hinged or otherwise connected to the base portion in such manner that it may be brought into a suitable position when required for writing, while when not required 35 for use it may be folded upwardly out of the way with its free end abutting against the telephone, or may be pushed out of the way in the channel between the disks. The base portion is also provided with an extension adapted to support a roll of paper. The paper from the roll is adapted to pass 40 through the channel in the base portion and on to the writing base, and it may be retained in position thereon by means of 45 guides formed by turning over the edges of the writing base.

According to another construction the base portion of the appliance is dispensed with, and the writing base is provided with 50 means whereby it may be attached to the pillar of the telephone above the base of the telephone. In this construction the writing base is attached to, or forms part of, a truncated cone, pyramid, or the like, fitting 55 around the telephone and above the telephone base.

A roll of paper may be provided as in the constructions hereinbefore mentioned, or if desired, a pad of paper may be provided on the writing base. 60

The invention further comprises certain features of construction which will appear from the following description with reference to the drawings, and will be pointed out in the claims. 65

Referring to the drawings:—

Figure 1 is a side elevation of one example of appliance.

Fig. 2 is a rear elevation, Fig. 3 is a front elevation, and Fig. 4 is a plan view of the 70 example of appliance shown in Fig. 1.

Fig. 5 is a perspective detail view illustrating a modification.

Fig. 6 is a sectional plan of the base member detached and illustrating the modified 75 form of writing base.

Fig. 7 is a section on line A—B Fig. 6.

Fig. 8 is a cross section illustrating an alternative construction of the base.

Referring to Figs. 1 to 4 inclusive of the 80 drawings the base portion of the appliance preferably comprises two substantially circular plates 1 and 2 separated by distance pieces 3. These parts are suitably secured together as by brazing, soldering, rivets, or 85 screws, in such a manner as to form a channel between, and transversely of, the two disks 1 and 2. The base portion thus formed is adapted to be clamped to the base of an ordinary table telephone by means of 90 wire clips 4. These clips are U shaped in plan and their two arms engage in holes formed in the edge of the upper plate 2 and also in holes formed in lugs 5 soldered, brazed or otherwise secured, to the lower 95 plate 1 of the base so as to hold the two plates together. These clips are preferably so bent as to take a spring grip on the base of the telephone. The two arms of each clip may diverge so as to take a spring grip in 100 the lugs 5, or may be secured therein if desired. Preferably two of these clips 4 are arranged at diametrically opposite points of the base, and one is preferably arranged to be diametrically adjustable so as to fit telephones having different sized bases. For 105 this purpose the clip on one side may be firmly soldered or secured in the lugs 5, while the clip on the opposite side has extended arms which are slideable in the lugs 5. 110

The rear portion of one of disks 1, 2, but preferably of the upper disk 2, is formed

with an extension which is suitably bent to form a bracket 6 for the support of the paper carrying drum 7. The paper carrying drum 7 may be formed as shown by a prolongation of the bracket 6 suitably bent to cylindrical shape, or it may be formed separately and hinged to the support 6. The paper roll is preferably rotatably mounted in the drum 7. The paper roll may be supported within the drum 7 upon a central spindle 8 securely attached to the middle of one of the end plates of the drum. The opposite end plate of the drum may be removable so that the paper roll can be inserted and this end plate may be secured in position by a nut screwing on to the end of the spindle 8. In front of the appliance the lower disk 1 is formed with an extension or extensions 11 adapted to be curved over in such manner as to embrace a hinge pin 9. The hinge pin 9 is also adapted to be embraced by bent projections formed on the writing base 10. The writing base 10 is preferably of metal and has its edges turned over to form guides 12 for the edges of the paper strip.

The paper strip is adapted to pass from the drum 7 through the channel between the disks 1 and 2 and over the surface of the writing base 10 with its edges guided by the guides 12. When not required for use the writing base 10 may be turned upward into the position shown in dotted lines in Fig. 1, and the underside of the writing base may conveniently be provided with advertising matter. If this advertising matter is embossed on the writing base a false base may be inserted to provide a smooth surface for the paper to rest upon.

According to the modification illustrated by Fig. 5 the writing base 10 is adapted to be pushed into the channel between the two disks 1 and 2 when not required for use. For this purpose the projection or projections 11 on the lower disk 1 may be conveniently bent only partially around the hinge pin 9 so that when the writing base 10 is pushed inwardly the hinge pin 9 disengages from the projections 11 and the writing base is free to be pushed into the channel. In order that the writing base 10 may be pulled out again when required it may conveniently be provided at its outer end with a curved tongue 13 by which it may be grasped with the fingers.

In the alternative construction of base as illustrated in Fig. 8, one disk only is employed, the base comprising a flat central lower part 12 having upwardly bent ends 13, lateral extensions of which are turned inwardly to provide upper parts 14 parallel to the base, the extreme ends being bent downwardly as at 15. The parts 15 act as the distance pieces and they form the transverse channel for the paper.

Any of the appliances hereinbefore described may be made from sheet metal suitably stamped, and bent to shape, and any of the parts not used as the writing base may have advertising matter applied thereto in any desired manner.

What I claim then is:—

1. Memorandum appliance for table telephones, comprising a base, means on said base for detachably securing it beneath the base of a table telephone, a channel formed by upper and lower parts of said base and by distance pieces between them, a flat support for paper carried by said base and located adjacent one end of said channel, a paper supply device located on the other side of the telephone to the said support and adjacent the other end of the channel, whereby the paper from the supply device can pass through said channel to the flat support.

2. Memorandum appliance for table telephones comprising a base, a fixed clip on one side of the base and an adjustable clip on base for detachably securing it beneath the base of a table telephone, a channel formed by the casing of said base, a flat support for paper carried by said base and located adjacent one end of said channel, and a paper supply device located on the other side of the telephone to the said support and adjacent the other end of the channel, whereby the paper from the supply device can pass through said channel to the flat support.

3. Memorandum appliance for table telephones comprising a base, means on said base for detachably securing it beneath the base of a table telephone, a channel formed between upper and lower parts of said base, and by distance pieces between them, a flat support for paper carried by said base and located adjacent one end of said channel, a paper supply device located on the opposite side of the telephone to said support and adjacent the other end of the channel, whereby the paper from the supply device can pass through said passage to the flat support.

4. Memorandum appliance for table telephones comprising a base, a fixed clip and an adjustable clip on said base for detachably securing it beneath the base of a table telephone, a channel formed between upper and lower parts of said base, and by distance pieces between them, a flat support for paper carried by said base, and located adjacent one end of said channel, a paper supply device located on the opposite side of the telephone to said support and adjacent the other end of the channel, whereby the paper from the supply device can pass through said channel to the flat support.

5. Memorandum appliance for table telephones comprising a base, including two disks of sheet material secured together in spaced relation with distance pieces between

them, means on said base for detachably securing it beneath the base of a table telephone, and a flat support for paper carried by said base.

- 5 6. Memorandum appliance for table telephones comprising a base, including two disks of sheet material secured together in spaced relation with distance pieces between them, means on said base for detachably 55
10 securing it beneath the base of a table telephone, a channel formed between upper and lower parts of said base and by distance pieces between them, a flat support for paper carried by said base and located adjacent 15
15 one of said channels, a paper supply device located on the opposite side of the telephone to said support and adjacent the other end of the channel, whereby the paper from the supply device can pass through said channel 20 to the flat support.

7. Memorandum appliance for table telephones comprising a base, including two disks of sheet material secured together in spaced relation with distance pieces between 25 them, a fixed clip and an adjustable clip on said base for detachably securing it beneath the base of a table telephone, a channel formed between upper and lower parts of said base and by distance pieces between 30 them, a flat support for paper carried by said base and located adjacent one end of said channel, a paper supply device located on the opposite side of the telephone to said support and adjacent the other end of the 35 channel, whereby the paper from the supply device can pass through said channel to the flat support.

8. Memorandum appliance for table telephones comprising a base, including two 40 disks of sheet material secured together in spaced relation with distance pieces between them, a fixed clip and an adjustable clip on said base for detachably securing it beneath the base of a table telephone, a channel 45 formed between upper and lower parts of said base and by distance pieces between them, a flat support for paper carried by said base and located adjacent one end of said channel, a paper supply device located 50 on the opposite side of the telephone to said

support and adjacent the other end of the channel, whereby the paper from the supply device can pass through said channel to the flat support.

9. Memorandum appliance for table telephones comprising a base, including two disks of sheet material secured together in spaced relation with distance pieces between them, means on said base for detachably 55
10 securing it beneath the base of a table telephone, and a flat support for paper carried by said base, said support having guides at opposite edges.

10. Memorandum appliance for table telephones comprising a base, including two 65 disks of sheet material secured together in spaced relation with distance pieces between them, means on said base for detachably securing it beneath the base of a table telephone, a channel formed between the upper 70 and lower parts of said base and by distance pieces between them, a flat support for paper carried by said base and located adjacent one end of said channel, said support having guides at opposite edges, a paper 75 supply device located on the opposite side of the telephone to said support and adjacent the other end of the channel, whereby the paper from the supply device can pass through said channel to the flat support. 80

11. Memorandum appliance for table telephones comprising a base, including two disks of sheet material secured together in spaced relation with distance pieces between them, a fixed clip and an adjustable clip on 85 said base for detachably securing it beneath the base of a table telephone, a channel formed between upper and lower parts of said base and by distance pieces between them, a flat support for paper carried by said base 90 and located adjacent one end of said channel, said support having guides at opposite edges, a paper supply device located on the opposite side of the telephone to said support and adjacent the other end of the channel, whereby the paper from the supply device can pass through said channel to the 95 flat support.

In testimony whereof I affix my signature.
JOHN McDONALD HATTERSLEY.
